(57) **CLAIM**

The ornamental design for a flip-to-side magnifier mount, as shown and described.

DESCRIPTION

FIG. 1 is an isometric view of a first embodiment of a flip-to-side magnifier mount, showing my new design;

FIG. 2 is another isometric view of the flip-to-side magnifier mount shown in FIG. 1;

FIG. 3 is a front elevational view of the flip-to-side magnifier mount shown in FIG. 1;

FIG. 4 is a rear elevational view of the flip-to-side magnifier mount shown in FIG. 1;

FIG. 5 is a left side elevational view of the flip-to-side magnifier mount shown in FIG. 1;

FIG. 6 is a right side elevational view of the flip-to-side magnifier mount shown in FIG. 1;

FIG. 7 is a top plan view of the flip-to-side magnifier mount shown in FIG. 1;

FIG. 8 is a bottom plan view of the flip-to-side magnifier mount shown in FIG. 1;

FIG. 9 is an isometric view of a second embodiment of the flip-to-side magnifier mount, showing my new design;

FIG. 10 is another isometric view of the flip-to-side magnifier mount shown in FIG. 9;

FIG. 11 is a front elevational view of the flip-to-side magnifier mount shown in FIG. 9;

FIG. 12 is a rear elevational view of the flip-to-side magnifier mount shown in FIG. 9;

FIG. 13 is a left side elevational view of the flip-to-side magnifier mount shown in FIG. 9;

FIG. 14 is a right side elevational view of the flip-to-side magnifier mount shown in FIG. 9;

FIG. 15 is a top plan view of the flip-to-side magnifier mount shown in FIG. 9;

FIG. 16 is a bottom plan view of the flip-to-side magnifier mount shown in FIG. 9;

FIG. 17 is an isometric view of a third embodiment of the flip-to-side magnifier mount, showing my new design;

FIG. 18 is another isometric view of the flip-to-side magnifier mount shown in FIG. 17;

FIG. 19 is a front elevational view of the flip-to-side magnifier mount shown in FIG. 17;

FIG. 20 is a rear elevational view of the flip-to-side magnifier mount shown in FIG. 17;

FIG. 21 is a left side elevational view of the flip-to-side magnifier mount shown in FIG. 17;

FIG. 22 is a right side elevational view of the flip-to-side magnifier mount shown in FIG. 17;

FIG. 23 is a top plan view of the flip-to-side magnifier mount shown in FIG. 17; and,

(Continued)

FIG. 24 is a bottom plan view of the flip-to-side magnifier mount shown in FIG. 17.

The broken lines shown in the Figures are included for the purpose of illustrating portions of the flip-to-side magnifier mount that form no part of the claimed design.
